UNITED STATES PATENT OFFICE.

LEO SAMPSON AND LORENZ MUTHER, OF CHICAGO, ILLINOIS; SAID SAMPSON ASSIGNOR TO SAID MUTHER.

IMPROVEMENT IN TUCK-CREASERS FOR SEWING-MACHINES.

Specification forming part of Letters Patent No. 157,933, dated December 22, 1874; application filed May 13, 1873.

To all whom it may concern:

Be it known that we, LEO SAMPSON and LORENZ MUTHER, of Chicago, in the county of Cook and State of Illinois, have invented a certain Improvement in Tuck-Creasers, of which the following is a specification:

Our invention relates to certain improvements in tuck-creasers for sewing-machines.

In the drawings, Figure 1 represents a plan view of the invention complete; Fig. 2, a sectional side elevation.

Our invention consists in certain combinations and arrangements of devices and appliances, as hereinafter set forth and claimed, wherein—

A represents a vibratory lever, pivoted to a standard, B, on the bed-plate C. The front end of the lever is bent downward, and then forward in the form of a crook. (See dotted lines, Fig. 2.) The lever A is attached to a spring-bar, D, at d, and the spring-bar D fastened to the needle-bar of the sewing-machine by a hook-catch, D'; thus the parts A, D operate together. F is a spring-bar, a portion of the front end G of which is bent up at right angles, and forms a hinge, g, at its top. H is a plate or presser-leaf, hinged to the bar F at g, and swinging thereon. This plate H, about midway of its length, is bent and curved slightly upward at H'. I is an ear, formed on the plate H' by cutting a narrow strip from the side, and bending and shaping it in the desired form. E is a stud or projection on the base-plate C, over which the material to be creased is placed, and B is a gage-plate for regulating the width of tuck.

The spring presser-bar F and the presser or creaser leaf H H', with its opening ear I, are constructed of only two pieces of metal, in the form shown, and united by the hinge g. Thus a very simple, cheap, and effective tuck-creaser is secured, and one not liable to be injured or to get out of repair.

The operation is as follows: The material to be creased is placed over the spur E, and made to move over it as the machine feeds the material forward, thereby raising that part of the cloth to be creased. The needle-bar of the machine forcing down the spring-bar D, and with it the lever A, the curved end of the lever comes in contact with the curved portion H' of the creaser H, forcing the bar F, with the creaser H, downward and over the material on the stud E. The leaf H' being closed over the material, it is sharply creased or pinched between the parts G H, and over the stud E.

We are aware that a tuck-creaser has before been made operating in somewhat of a similar manner as ours, such as in the patent of Babcock, No. 143,741, issued October 21, 1873. We do not, therefore, broadly claim a tuck-creaser provided with a hinged presser-leaf, and operated by a spring-lever; but

What we do claim as new, and desire to secure by Letters Patent, is—

The tuck-creaser for sewing-machines herein described, consisting of the spring-bar F, its end G bent up some distance at right angles to form a hinge, g, rocker or presser, consisting of a leaf, H, hinged to the bar F, curved upward portion H', provided with the ear I, which forms part of same, the parts F, H, H', and I being constructed of two pieces of metal, formed and united as set forth and shown, in combination with the stud or projection E on the bed-plate C, all constructed, arranged, and adapted to operate substantially as and for the purposes described.

LEO SAMPSON.

LORENZ MUTHER.
